(57) **CLAIM**

The ornamental design for a radiation detector, as shown and described.

DESCRIPTION

FIG. 1 is a front perspective view of a radiation detector; FIG. 2 is a front elevation view of the radiation detector of FIG. 1; FIG. 3 is a rear elevation view of the radiation detector of FIG. 1; FIG. 4 is a right side view of the radiation detector of FIG. 1; FIG. 5 is a left side view of the radiation detector of FIG. 1; FIG. 6 is a top view of the radiation detector of FIG. 1; and, FIG. 7 is a bottom view of the radiation detector of FIG. 1. The broken lines represent structure or features that form no part of the claimed design.
